UNITED STATES PATENT OFFICE.

AUGUST SCHUBERT, OF ONEIDA, NEW YORK.

VEHICLE.

SPECIFICATION forming part of Letters Patent No. 578,270, dated March 2, 1897.

Application filed August 17, 1896. Serial No. 602,952. (No model.)

To all whom it may concern:

Be it known that I, AUGUST SCHUBERT, of Oneida, in the county of Madison and State of New York, have invented new and useful 5 Improvements in Vehicles, of which the following, taken in connection with the accompanying drawings, is a full, clear, and exact description.

This invention relates to the class of wagons 10 which have the main portion of the body between the axles depressed to a plane beneath the axles.

The object of the invention is to provide such wagons with ample and safe spring-supports 15 for the body and at the same time couple the body securely to the axles, so as to relieve the springs from the strain incident to the draft exerted on the vehicle when in motion; and to that end the invention consists in the novel 20 construction and combination of parts hereinafter described, and set forth in the claims.

In the annexed drawings, Figure 1 is a side view of a wagon embodying my invention. Fig. 2 is an enlarged side view of the front 25 portion of the wagon minus the wheels. Fig. 3 is a rear view of the central portion of the front axle with the spring and portion of the reach connected to said axle. Fig. 4 is an enlarged inverted plan view of the lower fifth- 30 wheel and its connection to the body of the wagon. Fig. 5 is a central vertical transverse section of the front axle and parts connected thereto, taken on line Y Y in Fig. 3. Fig. 6 is a transverse section on line X X in Fig. 5. Fig. 7 is a vertical longitudinal section of the 35 rear portion of the body and its connection to the axle, and Fig. 8 is a top plan view of one of the end portions of the rear axle.

Similar letters of reference indicate corresponding parts.

A and A' denote, respectively, the front and rear axles, and B the body, which latter has the portion between the axles depressed to a plane beneath said axles, as shown at B'. The 45 bottoms of the end portions, as well as the bottom of the depressed central portion, are horizontal, as shown in Fig. 7 of the drawings.

The body is supported on the axles by means of suitable interposed springs, preferably by 50 an elliptic cross-spring C at the front end and by elliptic side springs C' at the rear end. The front end of the body is connected to the top

of the spring by means of a fifth-wheel D back of the spring. The top circle-plate of said fifth-wheel is secured to the body B, and 55 the bottom circle-plate is formed with a saddle S, which rides on the top of the spring C and is fastened thereto by clips i i in substantially the same manner as shown in my United States Letters Patent No. 506,376, dated Oc- 60 tober 10, 1893.

The depressed portion B' of the body is connected to the front running-gear by means of the fifth-wheel D', the top circle-plate a of which is fastened to the under side of a forward extension B² of the bottom of the depressed body portion B', and the bottom circle-plate a' is pivoted to the top circle-plate by the king-bolt b and connected to the front running-gear by a reach c, fastened to said bottom circle-plate a' and extending forward therefrom and thence vertically upward, as at c', and terminated with a bifurcation, the free ends c² of which are bent horizontally to lie on the under side of the top portion of the 75 springs C, to which they are fastened by the clips i i, as shown in Fig. 5 of the drawings.

In order to obtain a more positive hold on the front axle, so as to effectually couple the wagon-body to said axle, I attach to the axle 80 or to the bolster d thereof a vertical box d', through which the vertical reach portion c' passes, and is permitted to slide vertically therein and move with the spring in its vertical vibrations.

To prevent rattling, I apply to the inner sides of the box d' a lining d², of leather or other suitable material. The reach c extends also rearward from the circle-plate a', as shown at c³, and terminates with a reverse 90 turned hook c⁴, by which it engages the rear edge of a segmental plate P, which is concentric with the fifth-wheel B², and is fastened to the under side of the depressed central portion B' of the wagon-body, as more 95 clearly shown in Fig. 4 of the drawings. Said hooked end portion c⁴ of the reach is allowed to freely slide lengthwise of the segmental plate and thus accommodate itself to the turning of the front axle. By hooking 100 the reach on said segmental plate the king-bolt b is greatly relieved from the draft of the reach.

The front end portion of the body B and

the bottom extension B^2 are reinforced by 5 braces e e , attached to the central portion of the upright end of the depressed body portion B' and extending forward and to one of the cross-bars f , by which the body is mounted on the upper fifth-wheel, and to the top of the body extension B^2 , where it may be secured by the king-bolt b , as more clearly seen in Fig. 2 of the drawings.

10 The rear end of the body B , I prefer to support on the rear axle A' by means of elliptic side springs C' , and in order to obtain a more positive connection of the body to said axle I employ two reaches t t , attached at one end to the depressed body portion B' and at the opposite end to the rear end portion of the body, and form each of said reaches with an intermediate vertical portion t' , by which it slides in one of the vertical boxes l , attached 20 to the end portions of the axle A' . These boxes I also line with leather or other suitable material l' to prevent rattling.

What I claim as my invention is—

1. The combination with the front axles 25 and centrally-depressed body, of a spring supporting the front portion of the body on said axle, a fifth-wheel pivoted back of the axle and connected at opposite ends respectively to the spring and to the body and provided with a vertical intermediate portion 30 sliding in a vertical box on the axle and thereby coupling said body longitudinally to the axle.

2. The combination with the front axle and 35 the body formed with a depressed central portion, of a spring mounted on said axle, a fifth-wheel pivoted back of said axle and connecting the front portion of the body to the spring, a fifth-wheel on the depressed portion of the body, and a reach connecting the latter fifth-wheel to the front running-gear and provided 40 with an intermediate vertical portion sliding in a vertical box fixed to the front axle, as set forth.

45 3. The combination with the front axle, of the body formed with a depressed central portion and with a forward extension on the bottom of said depressed portion, a spring mounted on said axle, a fifth-wheel connected to the 50 under side of the front portion of the body

and supported on the spring, a fifth-wheel connected to the aforesaid forward extension of the bottom of the depressed portion of the body, a segmental plate secured to the under side of the body back of and concentric with 55 the lower fifth-wheel, a vertical box fastened to the front axle, and a reach connected to the king-bolt of said lower fifth-wheel and having its rear end hooked and sliding lengthwise on the aforesaid segmental plate, and 60 the front end of said reach secured to the top portion of the spring and formed with an intermediate vertical portion sliding in the vertical box fixed to the axle, substantially as set forth and shown. 65

4. The combination with the body formed with a depressed central portion and the rear axle back of said depressed portion, springs supporting the rear portion of the body on said axle, reaches adjacent to the sides of the 70 body and attached at opposite ends to the depressed portion and rear portion of the body and formed with intermediate vertical portions, and vertical boxes fastened to the rear axle and embracing the vertical portions of 75 the reaches, as set forth.

5. In combination with the axles, the body formed with a depressed central portion and springs supporting said body, vertical boxes on the axles, reaches formed with vertical 80 portions sliding in said boxes, and antirattling linings on the inner sides of said boxes, as set forth.

6. In combination with the front running-gear, the wagon-body formed with a depressed 85 central portion and with a forward extension of the bottom of said depressed portion, two fifth-wheels attached respectively to the front end portion of the body and to the aforesaid extension, and braces secured to the central 90 portion of the upright end of the depressed body portion and extending forward and to the aforesaid portions of the wagon-body, as set forth.

In testimony whereof I have hereunto 95 signed my name this 24th day of July, 1896.

AUGUST SCHUBERT. [L. S.]
